INVENTOR

PHILIP HOGAN

BY *G. P. Cornwall* ATTY.

UNITED STATES PATENT OFFICE.

PHILIP HOGAN, OF ST. LOUIS, MISSOURI.

POLE PROTECTOR.

Application filed April 28, 1922. Serial No. 557,086.

To all whom it may concern:

Be it known that I, PHILIP HOGAN, a citizen of the United States, residing at the city of St. Louis, State of Missouri, have invented a certain new and useful Improvement in Pole Protectors, of which the following is a full, clear, and exact description, such as will enable others skilled in the art to which it appertains to make and use the same, reference being had to the accompanying drawings, forming part of this application.

This invention relates to a new and useful improvement in pole protectors, the object being to provide a sectional splice, the sections of which are separable so that they may be employed in connection with poles of different diameters.

It is well known that wooden telegraph and telephone poles decay and become weak at a point coinciding with the surface of the ground or earth in which they are embedded. This weakness may be occasioned by boring insects or rotting of the wood, with the result that while the butt and top of the pole after a few years usage may possess a large percentage of their original strength, the weakness from the above mentioned causes will commence to develop and continue to develop as the age of the pole increases, at a point where the pole should be comparatively strong. Hence, strains occasioned by wind, snow, ice, etc., can not be successfully resisted, and the poles will break.

My improved sectional splice is preferably made of separable pieces, each having a concave inner face adapted to receive poles of different diameters, each section accommodating itself to the taper, if any, of the pole upon which it is used. These sections are reinforced by outwardly extending radially disposed ribs or reinforcing projections deepest at approximately their middle portions and tapering thence towards the top and bottom edges of the sections. The sections are preferably made of cast metal such as steel or iron, the latter being malleableized and galvanized, if desired, to prevent corrosion. These reinforcing ribs are provided with means for receiving and co-operating with band rods by which the sections are secured in position on the pole to be spliced and strengthened. These band rods or irons when tightened, tend to flex the sections so as to cause them to closely fit the pole, thus adapting said sections to poles of

different diameters or tapers, and such other irregularities, such as knots or protuberances which may be encountered.

Figure 1 is a sectional view of my pole protector as applied in position on a wooden telegraph or telephone pole.

Figure 2 is a top plan view of the same.

Figure 3 is a detail view of one of the reinforced splices.

Figure 4 is a sectional view through a modified form.

Figure 5 is a side elevational view of the form shown in Figure 4.

In the drawings, 1 indicates the lower end of a telegraph or telephone pole, which is shown as being deteriorated by boring insects or rot, producing a reduced and weakened portion 2 approximately in the plane of the ground line.

3 indicates a section of my improved splice, preferably concavo-convex, from the outer face of which extend vertically disposed reinforcing ribs 4. These ribs are radially disposed with respect to the curvature of the splice sections and are deepest at their middle portions, tapering towards the top and bottom edges of the section.

5 are notches in the outer edges of these reinforcing ribs near their upper and lower extremities, which notches are adapted to receive hand irons or rods 6 which are designed to encircle the pole and by means of nuts 7 force the splice sections to flex and hug the pole above and below its weakened portion. In practice, it may be found unnecessary to use the band rods at the bottom of the splice sections, as these are buried in the ground and need not be tightly clamped around the buried portion of the pole. Each splice section is preferably less than a half circle so that the side edges are more or less separated when the sections are applied in position on a pole.

In Figures 4 and 5, I have shown a modification in which one of the webs is provided with an enlarged portion 8 formed with openings for receiving the ends of the band rod 6, the nut 7 of the band rod being applied on the ends thereof and on opposite sides of the lug 8, whereby when said nuts are tightened, the band rod will clamp the sections tightly in position on the pole.

What I claim is:

1. In a pole protector, a pair of semi-cylindrical plates, integral exterior longitudinal ribs on each of said plates, said ribs being

of greatest depth intermediate the ends of the plates and tapering toward the ends thereof, a tie rod extending over said ribs for clamping said plates toward each other 5 on a pole, and means for preventing said rods from slipping toward the ends of said ribs.

2. A pole protector comprising two semi-cylindrical sheets which may be placed 10 about a pole and are provided with integral outwardly extending longitudinal ribs for stiffening the sheets longitudinally, said ribs tapering toward the ends of the sheets and being notched, and a rod passing around the 15 sections over all of said ribs but one and seated in the rib notches and having its ends threaded, projecting through said one rib and secured on opposite sides thereof by nuts.

20 3. In a pole protector, a pair of concavo-convex plates each having longitudinal re-

inforcing ribs on its convex face, one of said ribs being apertured and extending outwardly beyond the edges of the other ribs, and a rod for clamping said plates to a post 25 having ends which extend through said apertures in opposite directions and are held against retraction through the apertures.

4. In a pole protector, a pair of concavo-convex plates each having longitudinal reinforcing ribs on its convex face presenting inclined edges, said ribs being provided with a series of notches arranged in a helix about the two plates, and a clamping rod seated in said notches to prevent its sliding along the 30 inclined edges of the ribs, the ends of said rod overlapping and each terminating adjacent to one of said ribs and secured against movement transversely of the latter.

In testimony whereof I hereunto affix my 35 signature this 19th day of April, 1922.

PHILIP HOGAN.
